C. HAMMER,
BAND RECEPTACLE CLOSURE,
APPLICATION FILED OCT. 19, 1918.

1,335,233.

Patented Mar. 30, 1920.

Inventor:
Charles Hammer,
Wm. J. Reid.

By his Attorney

UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

BAND RECEPTACLE-CLOSURE.

1,335,233.

Specification of Letters Patent. Patented Mar. 30, 1920.

Application filed October 19, 1918. Serial No. 258,880.

To all whom it may concern:

Be it known that I, CHARLES HAMMER, a citizen of the United States, residing at Queens, in the county of Queens and State 5 of New York, have invented certain new and useful Improvements in Band Receptacle-Closures, of which the following is a specification.

This invention relates to closures for receptacles of the wide-mouthed variety, and is particularly adapted to be secured on a receptacle provided with a flange on the outer wall below the top, around which the closure is secured.

15 The object of the present invention is to provide a closure for a wide-mouthed receptacle, in which a separate member is provided to secure the top closing member in position on top of the receptacle, by engagement with the flange on the receptacle; and which closure can be readily loosened for removal by merely pulling on a tongue or extension of the sealing member.

In the accompanying drawing showing 25 one embodiment of my invention, Figure 1 shows the closure in sealing position on a receptacle. Figs. 2 and 3 show the principal members of the closure, and Fig. 4 the gasket for the same. Fig. 5 shows the receptacle on which the closure is sealed in Fig. 1. Fig. 6 is a fragmentary view in section of the closure as first applied, and Fig. 7 is a similar view with the parts in sealing position; and Fig. 8 shows in section the 30 closure sealed on another form of receptacle.

The closure as shown comprises essentially two members, a cap member 10, shown in Fig. 3, and a ring or band member 11, shown separately in Fig. 2. The cap member 40 comprises a flat disk 12 having a comparatively short flange 13 projecting downwardly of cylindrical form. Preferably the disk connects with the cap by a comparatively shallow arch portion 14, as shown, 45 that forms a kind of bead on top of the cap, and provides a shallow channel inside of the cap, that will coöperate with a gasket 15. The latter is shown of ring form, of a size to be inserted in the cap, as shown in 50 Fig. 6.

The band or ring member 11 is in the form of a flat band that is wider than the flange portion 13 of the cap, and is provided with an inwardly extending flange 16

at the top, that will engage the marginal 55 portion 14 of the cap member 10, see Fig. 6, and which flange may be given a slightly downward bend as shown. One end of the band 11 is provided with an extension at the intermediate portion in the form of a 60 tongue 17, that will lap the other end of the band, but does not have any interlocking engagement therewith.

This cap is designed particularly for closure of a receptacle or jar having a flange 65 a short distance below the top, and is especially adapted for use with the receptacle illustrated in Figs. 5, 6 and 7. This comprises a sheet metal body 7 having a flange formed by bending outwardly at 18, then 70 upwardly as at 19, and then inwardly as at 25, whereby is produced a flange in which the lower wall extends transverse to the body to form a sealing shoulder, see Fig. 5. This receptacle also has the upper edge bent 75 outwardly to form a rounded top or bead as at 20, and which does not project outwardly as far as flange 21, just described.

The gasket 15 is placed on the top of the receptacle to engage the bead 20, and the 80 cap is placed thereon to engage the gasket, with the flange 13 projecting downwardly against the bead or rim 20, see Fig. 6. Thereupon the ring member 11 is placed over the cap to have its flange 12 engage 85 the top member, whereby the ring or band 11 will project downwardly in contact with the flange 21 of the receptacle, and its lower edge will project below this flange 21, as shown in Fig. 6. By the application of 90 downward pressure on top of the band and cap, these members will move downwardly and compress the gasket 15 between the bead 20 and the adjacent portion of the cap, see Fig. 7. The flange 13 of the cap will pass 95 downward by the bead 20, but will not reach the flange 21 of the receptacle. This downward movement will cause the lower edge of the band 11 to project somewhat farther below the flange 21, and thereupon lateral 100 pressure is inserted inwardly on the projecting edge of the band 11, to bend it to extend transversely inward to engage the lower wall 18 of the flange 21, as shown in Figs. 1 and 7. This will securely retain the 105 band member in this position, and it will secure the cap and gasket in the desired sealing position.

As shown in Fig. 1 the tongue 17 of the band 11 projects in engagement with the outer wall of the other end of the band, and does not interfere with the upper and lower 5 flange portions of the band. No locking means is needed as the flange portion of the band extends practically throughout the periphery of the flange 21. To remove the closure it is only necessary for the user to 10 grasp the tongue 17 and pull it outwardly, when the band will gradually yield throughout its length and will be removed from the cap and receptacle. This will leave the cap free to be lifted off of the vessel.

15 In Fig. 8 is shown the same closure applied to a receptacle of considerable thickness of side wall instead of being of sheet metal. The receptacle is provided with a flange 22 below the upper portion 24, which 20 flange has a transverse bottom wall 23. This flange will coöperate with the band in substantially the same manner as with the other form of receptacle, and the closure is applied, and pressed downwardly, and the 25 projecting lower edge of the band is bent inwardly to engage the flange, as with the other form of receptacle.

The receptacle shown in Figs. 5, 6 and 7 is not claimed herein but forms subject 30 matter of another application filed by myself, Ser. No. 258,878.

What I claim is:—

The combination of a receptacle having its upper edge rolled outwardly to form a bead, the wall below the bead being bent 35 outwardly and then downwardly and then inwardly to form a sealing shoulder, with the said bead located inside of the outer wall of the shoulder portion, and a closure for the receptacle comprising a disk having a 40 flange portion connected with the disk by an arch portion, said disk member being adapted to be placed on the receptacle outside of said bead with the flange located 45 inside of the outer wall of the said shoulder portion, a gasket located in the arch portion of the disk member to be compressed thereby against said bead, and a ring member adapted to pass down around the said flange portion of the disk member and around the 50 shoulder member and provided with an inwardly extending flange at the top arranged 55 to engage the arch portion of the disk member, said ring member extending down below said shoulder portion to be bent inwardly around the shoulder portion to retain the gasket compressed between the disk member and the said bead of the receptacle.

Signed at New York city, N. Y., on Oct. 17th 1918.

CHARLES HAMMER.
